UNITED STATES PATENT OFFICE

116,027

DESIGN FOR A TRAILER COUPLER OR SIMILAR ARTICLE

Bertron G. Harley, Saco, Maine

Application January 5, 1939, Serial No. 82,173

Term of patent 14 years

To all whom it may concern:

Be it known that I Bertron G. Harley, a citizen of the United States, residing at Saco, county of York, State of Maine, have invented a new, original, and ornamental Design for a Trailer Coupler or Similar Article, of which the following is a specification, reference being had to the accompanying drawing, forming part thereof.

In the accompanying drawing:

Figure 1 is a perspective view of a trailer coupler or similar article embodying my design, with the ball-retaining key in lowered position;

Figure 2 is a fragmentary view corresponding to Fig. 1, except that the ball-retaining key is in raised position;

Figure 3 is a fragmentary bottom view; and
Figure 4 is a fragmentary side elevational view.

The important or essential feature of my design resides in the portions shown in solid lines.

Reference is made to my co-pending design patent applications—Serial No. D-77,722, and D-77,723, both filed June 10, 1938, of which this case is a continuation in part.

I claim:

The ornamental design for trailer coupler or similar article, as shown and described.

BERTRON G. HARLEY.
